Wm. D. Bell.

INVENTOR,
Charles O. Michel,
BY
John Stewart,
ATTORNEY.

UNITED STATES PATENT OFFICE.

CHARLES O. MICHEL, OF HOBOKEN, NEW JERSEY.

INVALID-CRUTCH.

1,292,503.

Specification of Letters Patent. Patented Jan. 28, 1919.

Application filed July 8, 1918. Serial No. 243,780.

To all whom it may concern:

Be it known that I, CHARLES O. MICHEL, a citizen of the United States, residing at Hoboken, in the county of Hudson and 5 State of New Jersey, have invented certain new and useful Improvements in Invalid-Crutches, of which the following is a specification.

This invention relates to invalid crutches, 10 and its object is to provide a crutch which will afford elastic support to the user, and particularly to his shoulder and arm, thus to eliminate the shock incident to impact of the crutch with the ground and materially 15 reduce the fatigue which rigid crutches are well known to cause. A further object is to provide a yielding crutch which may be manufactured at minimum cost and will be exceedingly strong and durable notwithstanding it comprises movable parts.

In the accompanying drawing of the improved crutch,

Figure 1 is a side elevation;

Fig. 2 is a side elevation of the upper part 25 of the crutch, on a larger scale;

Fig. 3 is a sectional view on the line 3—3 of Fig. 2;

Figs. 4 and 5 are sectional views on the lines 4—4 and 5—5 of Fig. 1; and

Fig. 6 shows the upper part of the crutch with a certain flexible sheath housing the same.

The body structure of the crutch includes 35 two upright members *a* *a* preferably converging downwardly and terminating in the foot *b* over which is fitted a vertically yielding ferrule *c* containing a cushion in the form of a spiral spring *d*, the ferrule being retained on the foot by the slot and pin connection *e* therewith.

The head portion of the crutch is constructed as follows: There is a lower or fixed section *e* provided with a recess *f* in its upper part—being therefore in effect bifurcated—and having a pair of downwardly extending lugs or projections *g*. The upper ends of the members *a* are secured by screws *h* or otherwise to the outer faces of these two lugs. There is also an upper or 50 downwardly yielding section *i* which forms the shoulder support proper of the crutch and to this end may be suitably padded, as at *j*; this section has the downward extension *k* adapted to fit the recess *f* and move 55 up and down therein. The lower section forms a guide for the upper section, and

this is accomplished by providing tongue and groove connections between the extension *k* of the section *i* and the inner faces of the bifurcated upper part of the section *e*; 60 the tongues are indicated at *l* and the grooves at *m*.

A cushion means for the upper section *i* and preferably consisting of two springs is arranged in the recess *f* and constructed as 65 follows: Each spring consists of a stout wire having its end portions formed as alined coils *n* *n*, its ends proper *o* extending in one direction from the coils and its intermediate portion *p* (which is substantially a 70 loop) in the opposite direction. A short length of tubing *r* affords an axial support or bearing for the two coils *n*. The springs are arranged with their loops crossing as shown in Fig. 2, their coils being disposed 75 in the respective lower corners of the recess *f* and secured in place by stout wood screws *s* which are driven through suitable holes in the bearing pieces *r* and into the section *e*; the ends proper of the wires are inserted 80 in holes in the section *e* as shown in Fig. 2. To limit the upward movement of the springs chains *t* may be arranged to connect their extremities with the section *e*. The springs preferably bear slidingly on a metal 85 plate *u* attached to the under face of the section *i*. The upper section *i* is removably coupled to the lower section *e* by the pairs of strips *v* which are preferably secured to the opposite faces of the section *i* and are received in grooves *w* in the lower section *e*, 90 extending through staples *x* driven into the latter and having set screws *y* which, with the springs at the upward limits which the chains *t* afford and with the section *i* resting on the springs, abut the staples, so that 95 there will be no lost motion as to the section *i*; upon removing the set screws *y* the section *i* can be detached.

To cover the adjoining portions of the 100 sections *e* and *i* and the intervening mechanism I provide a flexible casing *z* which may be secured in place by lacing *2*, as shown in Fig. 6.

The hand-hold 3 has a hand grip 4 and 105 it moves in a vertical plane in alinement with the yielding shoulder support *i*. It has opposite tongue and groove connections 5 with the members *a*, between which it is arranged as shown best in Figs. 1 and 4. 110 In the actual construction shown the parts 3—4 consist of a block provided with a hand

opening to form the hand-grip 4, the result of this construction being that the hand grip has in effect upright extensions (one each side of said opening, rigidly connected below it by the material below the opening) each having vertically elongated guiding contact with the members *a* at 5; the hand-hold therefore is adapted to slide without binding between the members *a*. By means of bolts 10 6 a pair of plate springs 7 are secured to the members *a*, such springs overlapping and one bearing against the other and the latter against the under side of the arm support 3.

15 In view of the foregoing description and the accompanying drawing it will be seen that when the crutch is in use the user can apportion his weight to both the cushioned shoulder support *i* and cushioned hand-hold 20 3, the two yielding together, and that since the hand-hold is in vertical alinement with the shoulder support it is positioned where the arm can coact with the shoulder to best advantage in supporting the load.

25 Having thus fully described my invention, what I claim as new and desire to secure by Letters Patent is:—

30 1. An invalid crutch having a head portion formed in two sections, upper and lower, one section being vertically bifurcated and receiving the other and the lateral opposing faces of said sections within the bifurcation having vertical tongue-and-groove con-

nctions, and springs arranged between said sections within the bifurcation and affording 35 a cushion to the upper section.

2. An invalid crutch having a head portion formed in two sections, upper and lower, one section being vertically bifurcated and receiving the other and the lateral opposing 40 faces of said sections within the bifurcation having vertical tongue-and-groove connections, and crossed springs arranged between said sections within the bifurcation and affording a cushion to the upper section. 45

3. An invalid crutch including an upright body structure having upright spaced members, a downwardly yielding elastically supported block-shaped hand-hold extending across the space between said members, and 50 having an aperture to form a hand-grip, said hand-hold having elongated vertical tongues and said members having elongated vertical grooves forming sliding connections between them. 55

4. An invalid crutch including, with an upright body structure having upright spaced members, a downwardly yielding elastically supported block-shaped hand-hold arranged between said members and 60 apertured to form a hand grip and having vertical tongue-and-groove connections between its sides and said members.

In testimony whereof I affix my signature.

CHARLES O. MICHEL.
